UNITED STATES PATENT OFFICE.

ALFRED E. LYONS, OF SAN JOSE, CALIFORNIA.

AUTO-TOP.

1,353,925.

Specification of Letters Patent. Patented Sept. 28, 1920.

Application filed July 8, 1918. Serial No. 243,870.

To all whom it may concern:

Be it known that I, ALFRED E. LYONS, a citizen of the United States, residing at San Jose, in the county of Santa Clara, State of California, have invented certain new and useful Improvements in Auto-Tops; and I do hereby declare the following to be a full, clear, and exact description of the invention, such as will enable others skilled in the art 10 to which it appertains to make and use the same.

The invention relates to an automobile top, and more particularly to the class of telescopic or foldable automobile tops, commonly known as one man tops.

The primary object of the invention is the provision of a top of this character wherein side supports are entirely dispensed with and the top can be raised or extended and lowered or folded with despatch by one person, the top when raised or lowered being neat and attractive in appearance, and on the raising thereof no side supports are visible which ordinarily obstruct the view of 25 occupants of the automobile.

Another object of the invention is the provision of a top of this character wherein the same will be supported in extended position without the use of side supports or other equivalent structure, the top when folded being compact to occupy minimum space and without detracting from the neat and symmetrical contour of the body of the automobile.

A further object of the invention is the provision of a top of this character wherein the construction thereof is novel in form to assure strength and durability, and also which can be manufactured at a minimum 35 expense and is economical to install, the top being adaptable for touring cars or roadsters, and in fact can be installed on all makes of automobiles.

The invention furthermore has for an additional object to improve tops of the indicated character, in varying particulars, to the end that efficiency in operation may be promoted, as well as simplicity in construction and convenience in adjustment and control.

The invention will be particularly explained in the specific description following:

Reference is to be had to the accompanying drawing forming part of this specification, in which similar characters of refer-

ence indicate corresponding parts in all views.

Figure 1 is a fragmentary side elevation of an automobile body showing the top constructed in accordance with the invention raised or extended;

Fig. 2 is a fragmentary side elevation showing the top in its lowered or folded position;

Fig. 3 is a side elevation of the top with the cover removed, the top being extended;

Fig. 4 is a vertical longitudinal sectional view through the top, showing the same folded;

Fig. 5 is a fragmentary enlarged sectional view through the main or power bow showing in detail one of the slides and latch;

Fig. 6 is a sectional view on the line 6—6 of Fig. 5;

Fig. 7 is a fragmentary detail side view showing another slidable connection and latch of the frame of the top;

Fig. 8 is a fragmentary plan view of the part shown in Fig. 7, certain of said parts being shown by full lines and the other parts being shown by dotted lines;

Fig. 9 is a fragmentary vertical longitudinal sectional view;

Fig. 10 is a sectional view on the line 10—10 of Fig. 9.

In constructing a practical embodiment of the invention in accordance with the illustrated example the automobile top frame A is provided, preferably with a main bow 10 which has its side limbs formed with curved extremities 11 each having an eye for the pivotal mounting thereof on the stud pintle 12 of a bracket 13 fixed to the body B of the automobile. It is of course understood that two of these brackets are employed, and fixed to opposite sides of the body B near the back or at the rear end portion thereof. The body B shown in Figs. 1, 2 and 3 is of the touring car type, yet the same may be of the roadster type, and is illustrated merely for the purposes of showing the mounting and the operation of the top as will be hereinafter fully described.

Each limb of the main bow 10 is formed with a longitudinally disposed inverted substantially T-shaped groove 14 in which is slidably engaged the correspondingly shaped slide runner 15 of a pivot bearing 16. The slide runner 15 at opposite sides thereof carries anti-friction rollers 17 which travel

upon adjacent walls of the groove 14 so as to assure the smooth and easy movement of the bearing 16 as will be apparent. Swingly connected to the bearing 16 is 5 the side limb or arm 18 of a rear bow 19 which carries a swinging upwardly arched crown brace 20 for the top cover 21 which at its rear end is suitably fixed to the body B of the automobile and is folded and extended with the top frame in a manner 10 presently described.

Each bracket 13 carries a latch 22 which engages with a keeper 23 on the side arm or limb of the main bow 10 to lock the same 15 against swinging movement when the top is extended or raised.

Slidably supported on the rear bow 19 is the intermediate bow 24, the side limbs or arms of which are pivoted to bearings 25 20 each being constructed identically to the bearing 16 and slidably engaged in a longitudinal groove 26 formed in each of the arms or limbs of the said intermediate bow 24, the groove 26 being identical to the 25 groove 14 in each side limb or arm of the main bow of the frame of the top.

Pivoted to each bearing 25 is a swinging latch 27 adapted for detachable engagement with a keeper 28 on each side limb or arm of the intermediate bow 24 so as 30 to hold the latter against swinging movement when the top is raised to extended position. The bearings 16 each has pivoted thereto a latch 29 which is adapted for 35 detachable engagement with a keeper 30 on each side limb or arm of the rear bow 19 to lock it against swinging movement when the said top is raised or extended.

Pivoted in a slot in each side limb or 40 arm of the several bows is a locking dog 31 which is held in locking position through the medium of a coiled expansion spring 32 fitted within the limb or arm and the said dog is formed with a finger engaging 45 extension 33 which slidably fits in a guide 34 exteriorly of the limb or arm and when manually operated releases the dog from locking position with the slide runner. The dog 31 serves to lock the bearing when the 50 bows are extended.

Slidably supported upon the intermediate bow 24 is the break jointed front bow 35 to which the front end of the top cover 21 is fastened in any suitable manner. Each 55 limb of the front bow 35 is formed in two sections 36 and 37 respectively, the meeting ends of which are connected together through the medium of a break joint hinge 38 and the said section 37 is pivoted at 38 60 to a slide bearing 39 corresponding to either of the bearings 16 or 25 and slidably fitted in a longitudinal groove 40 formed in each of the side limbs or arms of the intermediate bow 24, the groove 40 being similar to 65 either of the grooves 14 or 26 hereinbefore

described. Mounted in each of the side limbs or arms of the bow 24 is a spring held hand released dog 41 for the side bearing 39 to lock the same when the front bow 35 has been moved forward to tighten 70 the top, the dog 41 being similar to either of the dogs 31. If the tension of the front portion of the distended top is not sufficient to hold the sections of the front bow open as far as their hinges 38 will permit, latches 75 and keepers like those already described may be employed for this purpose.

Mounted on the sections 37 of the side limbs or arms of the front bow 35 is a swinging front crown brace 42 which is 80 pivoted at 43 to the said sections 37 and together with the brace 20 prevents the sagging of the top cover 21 when extended. The sections 36 each of the front bow 35 at its pivoted end is formed with an angular 85 prop extension 44 for the front crown brace 42 to hold the same in bracing position for the cover 21 when the top is extended.

Pivoted connected with each side limb 90 or arm of the main bow 10 is a hinge jointed clamping device 45 which is adapted for detachable connection with the front bow 35 when the top frame is in folded position as shown in Fig. 4 of the drawing so as to 95 prevent relative displacement of the bows in their folded position while the top is lowered.

In the operation of the top, assuming that the same is extended or raised, the front 100 dogs 41 are released from the bearings 39 so that the sections 37 of the front bow can be moved rearwardly longitudinally of the intermediate bow 24 by the sliding of the bearings 39 in the side limbs or arms of 105 said intermediate bow. This reduces the tension on the cover, and next the sections of the front bow can be folded over onto each other with the front part of the cover between them, the bearings 39 run forward in 110 the intermediate bow, and the folded cover and folded front bow swing under said intermediate bow. Next the dogs 31 in the rear bow 19 are released from the bearings 25 which permits the said intermediate bow 24 115 to be moved rearwardly, and the latch 29 is released from the keeper 30 so that the said intermediate bow 24 can be swung close to and against the rear bow. The rear crown brace 20 is next folded on to the bow 120 19, and the dogs 31 in the main bow 10 are released from the bearing 16 whereupon the same are slid toward the pivoted end thereof, thus bringing the rear bow to lowered position. Next the latch 27 is disengaged 125 from the keeper 28 permitting the rear bow 19 to be folded against the main bow, and finally the latch 22 is disengaged from the keeper 23 to permit the main bow to be brought to lowered position and thus the 130

top is completely folded in the position shown in Figs. 2 and 4 of the drawings. The opening of the top will reverse this operation and a detailed explanation thereof has been omitted for the sake of brevity.

From the foregoing it is thought that the construction and manner of operation of the top will be clearly understood, and therefore a more extended explanation has 10 been omitted. However, it is contemplated to make changes, variations and modifications in the invention such as come properly within the scope of the appended claims without departing from the spirit of the 15 invention or sacrificing any of its advantages.

What is claimed is:

1. In a foldable top of the character described, the combination with the cover; 20 of a swingingly supported main bow, a rear bow slidably and swingingly connected with the main bow, an intermediate bow slidably and swingingly connected with the rear bow, a front bow carried by the intermediate bow, means for locking all bows against swinging from their positions which distend the cover, and means for locking the rear, intermediate, and front bows against sliding movement.
2. In a foldable auto top, the combination with the cover; of a pivotally supported main bow, other bows slidably and pivotally connected with each other and the rearmost with the main bow, the front bow being in 35 sections connected by a break-joint pivot,

and latches for holding the parts against pivotal movement and dogs for holding them against sliding movement out of their set positions which distend said cover.

3. In a top prop for autos, the combination with a main bow adapted to be supported by the body, and other bows, all bows having longitudinal grooves in their limbs; of a runner slidable in the groove of each bow and to which runner another bow is pivoted, a latch on the runner, a keeper on the pivoted bow adapted to be engaged by said latch when such bow is opened up, and means for fastening the runners at points within said grooves. 40 50

4. In a top prop for autos, the combination with a main bow adapted to be supported by the body, and other bows, all bows having longitudinal grooves in their limbs; of a runner slidable in the groove of each bow and to which runner another bow is pivoted, a latch on the runner, a keeper on the pivoted bow adapted to be engaged by said latch when such bow is opened up, and a spring-actuated dog mounted in each 55 bow at a point to lock the runner of the next bow with the latter in position to distend the top. 60

In testimony whereof, I affix my signature, in the presence of two witnesses.

ALFRED E. LYONS.
